UNITED STATES PATENT OFFICE.

ERNST KETZLER, OF CHICAGO, ILLINOIS.

SCOURING-MACHINE.

No. 872,823.

Specification of Letters Patent.

Patented Dec. 3, 1907.

Application filed April 16, 1906. Serial No. 311,943.

To all whom it may concern:

Be it known that I, ERNST KETZLER, a citizen of the United States, residing at Chicago, in the county of Cook and State of Illinois, have invented certain new and useful Improvements in Scouring-Machines, of which the following is a specification.

The subject of the present invention is a machine for scouring garments, fabrics, and similar articles and the object of the invention is to provide an improved machine by which the work can be done thoroughly and expeditiously.

Generally stated, the machine comprises a pair of revolute brushes, one of which is movable toward and from the other, means for revolving said brushes in opposite directions, and a work support having elongated openings through which the periphery 15 of one of the brushes projects a short distance so as to come in contact with the under side of the article being cleaned.

The machine has also minor features which are fully described hereinafter.

The invention consists in the features of novelty that are hereinafter described with reference to the accompanying drawings which are made a part of this specification, and in which

Figure 1 is a side elevation of a machine embodying the invention. Fig. 2 is a plan view thereof, all of those portions below the line X—X, Fig. 2, and above the line Y—Y, Fig. 1, being omitted. Fig. 3 is an enlarged detail.

The machine has a frame which may be of any desired construction. In the drawing it is shown as comprising two side castings, 1, made of angle iron, connected by any suitable number of tie-rods, 2, only the upper portion of the frame being shown in the drawing. Rising from each of the top horizontal beams of the frame are two standards, 3, which may be of L shape, one branch of the L being bolted to the beam while the other branch extends upward. To these standards the down-turned ends, 4, of a bar, 5, are adjustably secured by bolts or screws, 6, the opening in the one of the overlapping parts, 3 and 4, against which the heads of the screws bear, being elongated to permit the bar 5 to be adjusted vertically for a purpose that will appear presently.

The bars 5 are rigidly connected by a cross beam 7, preferably made of metal, the ends of which are secured by screws or other

suitable means to said bars. This beam enters into the construction of the work support, a portion of which consists of an imperforate table-like portion 8, which is adjacent to the brushes and freely accessible to the workman so that he may manually feed the goods to the brushes and manipulate them as freely as may be necessary. The table is preferably made of sheet metal, one margin of which is secured in a rabbet in the beam 7 and the outer portion of which is deflected downward and thence upward to form a trough, 9, for catching the water that flows off of the table and directing it to the side of the machine. 10 is a second beam, preferably made of metal, which extends from one to the other of the bars 5, and is adjustably secured to them by screw-bolts, 11, which pass through slots 12 in the bars 5. When the bolts 11 are tightened the connection between the beam and the bars 5 becomes rigid, and the beam assists in bracing and holding the bars 5 in place, but when the bolts are loosened the slots 12 permit the lateral movement of the beam 10 on the bars. These beams, 7 and 10, enter into the construction of the work support, the support being completed by a number of wires, 13, the ends of which are secured to the beams, 7 and 10, by any suitable means. As shown more clearly in Fig. 3 the ends of the wires are bent downward at right angles and are secured to the sides of the beams, 7 and 10, by clamping strips 14 through which screws 15 pass and have threaded engagement with the beams. The wires are located at such distance apart as to prevent the article being cleaned from following the lower brush hereinafter described. Secured to the beam 10, at each end, is a plate 16 carrying a threaded stem 17 which passes through a standard 18 rising from the bar 5 and receiving on the rear side of said standard a nut 19. By adjusting the nuts 19 on opposite sides of the machine the beam 10 may be drawn toward the standards so as to tighten the wires. This standard has also a horizontal arm 20 through which passes a screw 21 carrying a lock nut 22, for the purpose that will appear hereinafter.

It will be observed that as a result of forming a portion of the work support of a plurality of wires, said support has a plurality of resulting elongated openings, but I desire to have it understood that in its broadest aspect the invention is not limited

to the use of wires in order to provide these openings.

Located beneath the work support is a brush 23, the shaft of which is journaled in bearings 24 supported by the main frame. At one end the shaft projects and carries a pulley, 25, over which passes a crossed belt 26 which also passes over a pulley 27 on the driving shaft 28, upon which latter is mounted fast and loose pulleys, 29 and 30, respectively. As shown in Fig. 1 the upper periphery of the brush projects a short distance through the elongated openings in the work support so as to come in contact with the under side of the article being cleaned.

31 is the upper brush, which is movable toward and from the lower brush. Its shaft is journaled in the forward ends of arms 32, the rear ends of which are pivotally mounted upon the shaft 28 which is parallel with the shaft of the brush, so that their forward ends are capable of a pivotal movement, up and down, in planes perpendicular to the axis of the brush shaft. Upon the top side of each of the two boxes in which the shaft of the brush 31 is journaled is a pair of perforated ears 33, and between these ears is secured the end of a yoke 34 which extends from one box to the other and serves to brace the outer ends of the swinging arms 32 and prevent their lateral horizontal movement. The arms and yoke constitute a frame and the shaft 28, which occupies a fixed position, constitutes a fixed pivotal support for the frame, so that its free side which carries the brush may freely move upward and downward about said pivotal support, while at the same time it is restrained from any horizontal movement which would carry the brush backward and forward over the work support. To this yoke is secured a pair of eyes or rings 35 to which in turn are attached the branched ends 36 of a rope or cable 37, which latter is trained over a pulley, not shown in the drawing, and carries a weight 38 which over-balances the weight of the upper brush and its accessories and serves to lift it and hold it normally in elevated position.

50 For lowering the brush 31 to operative position treadle rods 39 are attached to the swinging arms 32, or to projections 40 carried by them, the lower ends of these rods being suitably connected with a treadle or foot-board, not shown in the drawings. Screws 21 adapted to engage the frame, form stops for limiting the downward movement of the brush and enabling the operator to hold the brush in proper relation to the lower brush without the effort that would be required if no stops were used. The stops are adjustable in order to compensate for the wearing away of the upper brush. These projections support a tube, 41, the side of 65 which, adjacent to the brush 31, is provided

with numerous perforations for discharging water on to the brush and this tube 41 is supplied with water through either of two pipes, 42 or 43, one of which is intended to supply soap water and the other of which is intended to supply clear water.

In order to prevent the water thrown off by the brushes from wetting the driving pulley and also to prevent it from falling on to the floor, a shield having an upright portion 75 44 and a horizontal portion 45 is provided. This shield is supported by brackets 46 secured to the main frame.

From the foregoing description, the operation of the machine is almost apparent. The 80 garment or article to be cleaned is placed upon the table and the brush 31 lowered into contact with the brush 23. The garment is then advanced into the bite of the brushes and by their action, their adjacent peripheries moving in the same direction, the garment may be fed between them and thoroughly scoured. It will be understood that the brush is lowered by pressure on the foot-board, not shown. When the garment has 90 been fed past the brushes, pressure upon the foot-board is removed and the weight 38 will elevate the brush 31 thus leaving the operators' hands at all times free to manipulate the garment.

95 The horizontal portion, 45, of the shield, serves also as a means for supporting that portion of the garment which passes over the rear edge of the work support.

When the brush 23 wears, or for any other 100 reason it becomes necessary to do so, the entire work support may be lowered by loosening the bolts 6.

What I claim as new and desire to secure by Letters Patent is:

105

1. In a scouring machine, the combination of two brushes located one above the other, a work support, having openings through which said brushes contact with each other and having a table-like portion adjacent to the brushes and freely accessible to the operator upon which he may manipulate the goods, means for revolving the brushes in opposite directions so that their contacting faces move away from the work-table, and 115 means for raising and lowering the upper brush, whereby the operator may manually feed the goods to the brushes and allow them to be drawn forward at any desired speed and, upon the lifting of the upper brush may 120 quickly withdraw the goods for manipulation on the work table, substantially as described.

2. In a scouring machine, the combination of two brushes, one located above the other, a work support, having openings through 125 which said brushes contact with each other and having a table-like portion adjacent to the brushes and freely accessible to the operator upon which he may manipulate the goods, means for revolving the brushes in 130

opposite directions so that their contacting faces move away from the work-table, a frame carrying the upper brush, a fixed pivotal support for the frame, the axes of the brush and pivotal support being parallel, and means for moving the free side of the frame up and down, about its pivotal support, whereby the upper brush is raised and lowered, whereby the operator may manually feed the goods to the brushes, substantially as described.

3. In a scouring machine, the combination of two brushes, one located above the other, and a work-support, having openings through which said brushes contact with each other and having a table-like portion adjacent to the brushes and freely accessible to the operator, means for revolving the brushes in opposite directions, a frame carrying the upper brush, a fixed pivotal support for the frame, the axes of the brush and pivotal frame being parallel, means for automatically lifting the free side of the frame and holding it normally elevated, and means for manually lowering it, substantially as described.

4. In a scouring machine, the combination of two brushes, one located above the other, and a work support, having openings through which said brushes contact with each other and having a table-like portion adjacent to the brushes and freely accessible to the operator, means for revolving the brushes in opposite directions, a frame carrying the upper brush, a fixed pivotal support for the frame, the axes of the brush and pivotal support being parallel, means for automatically lifting the free side of the frame and holding it normally elevated, treadle-mechanism for lowering it and stops for limiting its downward movement, substantially as described.

5. In a scouring machine, the combination of a work support, having elongated openings, a brush located below the support and projecting through said openings, means for revolving the brush, a brush located above said support, a frame carrying the brush, a pivotal support for the frame, the axes of the brush and pivotal support being parallel,

means for revolving the brush, means for raising and lowering the frame and means carried by the frame for discharging water on to the brush, substantially as described.

6. In a scouring machine, the combination of a work support having elongated openings through it, means for adjusting said work support vertically, a brush located below the support and projecting through said openings, means for revolving the brush, a brush located above the support and movable toward and from it, means for revolving it, and means for moving it toward and from the support, substantially as described.

7. In a scouring machine the combination with a work support of a plurality of parallel wires spaced apart to provide elongated openings, a laterally movable beam to which the ends of said wires are attached, and means for moving said beam laterally for applying tension to the wires, of a brush located below the support and projecting through said openings, means for revolving the brush, a brush located above said support, means for revolving it, and means for moving it toward and from the support, substantially as described.

8. In a scouring machine, the combination with a work support having side bars, a transverse beam, the ends of which are rigidly secured to said side bars, a transverse beam, the ends of which are adjustably secured to said side bars, whereby said beam may be adjusted laterally, a plurality of wires, the ends of which are secured to said beams, respectively, said wires being spaced apart to provide elongated openings, and means for moving the adjustable beam laterally to apply tension to the wires, of a brush located below the support and projecting through said openings, means for revolving it, a brush located above the support, means for revolving it, and means for moving it toward and from the support, substantially as set forth.
